(57) **CLAIM**

The ornamental design for a pocket, as shown and described.

DESCRIPTION

FIG. 1 is a front perspective view of a pocket showing my new design;

FIG. 2 is a front view of the invention;

FIG. 3 is a left side view of the invention;

FIG. 4 is a right side view of the invention;

FIG. 5 is a top view of the invention; and,

FIG. 6 is a bottom view of the invention.

The broken lines, circumscribing the pocket in FIG. 1, represent the boundary of the claimed design.

The broken lines, shown on the surface of the pocket in FIGS. 1 and 2, represent stitching.
